JOURNAL BOX WASTE GRAB PREVENTING
MEANSWilliam T. Bissell, Indianapolis, Ind., assignor to
Journal Box Servicing Corporation, Indianapolis, Ind., a corporation of Indiana

Application May 3, 1937, Serial No. 140,422

10 Claims. (Cl. 308—89)

This invention relates to means for preventing "waste grabs" in railway journal boxes. It frequently happens that journal bearings run hot by reason of the fact that the packing waste will be caught between the journal brass and the axle.

While it is realized that others have worked on the problem of preventing waste in the journal box from getting between the brass and the axle, it seems that the actual cause of this condition has been generally over-looked. When a railway car is bumped sufficiently hard, the journal brass will actually lift above and travel to one side of the axle within the limits of travel of the axle in the journal box. When this occurs, the axle will, in relation to the brass, travel diagonally downward toward one side of the journal box directly against the waste packing. Thus, the axle will apply pressure on the waste at this side of the box. The only way for this pressure to be relieved is for the waste to move around out of the way and thus be forced up on the opposite side between the axle and the journal box, which side is where the greatest opening exists between the brass and the axle. Consequently, when the brass again drops down into position on the axle, it is likely that some of this lifted waste will be caught therebetween.

It is a primary object of my invention to provide means which will automatically close off this opening and at the same time be normally in such position that there will be no interference with the proper lubrication of the axle and no interference with packing irons and the like.

These and further objects and advantages of the invention will become more apparent to those skilled in the art in the following description of the invention which is made in reference to the accompanying drawing, in which

Fig. 1 is a vertical transverse section through a conventional type journal box;

Fig. 2, a top plan view of the journal brass with the invention applying thereto;

Fig. 3, a side elevation of the invention applied to the brass; and

Fig. 4, a detail in section on the line 4—4 in Fig. 3.

Like characters of reference indicate like parts throughout the several views in the drawing.

Referring first to Fig. 1, the usual journal box 10 is provided with a curved floor on which is carried a quantity of oil saturated waste 11 of a sufficient depth to bear against the under side of the car axle 12. The usual journal brass 13 rests on the upper side of the axle 12 and is positioned between inwardly extending shoulders 14 and 15,

against which from their outer side abut the brass lugs 16 and 17, all in the usual and well known manner.

These shoulders 14 and 15 are cut away beginning at an elevation under the brass 13 to curve outwardly and downwardly into the wall of the box 10. Also, there is generally present within the box 10 inwardly extending portions 18 and 19 of the box wall to provide external clearance for bolts 20 and 21.

The packing waste extends throughout the length of the box 10 and around these projecting portions 18 and 19. The axle 12 is lubricated by picking up oil from the contacting waste 11 and having the axle carry this oil around under the brass 13. Excess oil is wiped off of the axle at the line of contact between the brass lining 22 with the axle. With properly shaped brasses, this excess oil will flow outwardly on the brass and drop back down on to the waste 11 without striking the axle. This excess oil serves to cool the axle 12 and carry away the heat generated by the turning of the axle under the brass.

With the foregoing construction and conditions in mind, I apply a pair of gates to the brass 13. Each gate 23, Fig. 3, consists of a plate of metal hinged to a bracket 24 which is removably attached to the side of the brass 13. In the form herein shown, a plate 23 is provided with a pair of pins 25 and 26 spaced above the upper edge of the plate and directed one toward the other.

The bracket 24 consists of a horizontally disposed length of metal and having upturned ends 27 and 28, and their respective fingers 29 and 30 turned over from the upper portions of these ends to be directed substantially one toward the other in approximate parallelism with the horizontally disposed bar. On the outer sides of these ends 27 and 28 are provided suitable sockets to receive the pins 25 and 26 in such a manner that will permit the plate 23 to hang freely from the bracket 24 and swing therefrom. These sockets may be formed as indicated in Fig. 4 to have an initial U-shape in cross section with an opening at the top so that when the plate 23 is to be attached to the bracket 24, the plate 23 may be presented to the bracket to have the plate's plane horizontally disposed, in order to drop the pins 25 and 26 downwardly into these sockets, whereupon the plate 23 may be released to allow it to swing downwardly to a vertically disposed position. The upper ends of the respective sockets may then be bent inwardly a sufficient distance so as to prevent the accidental displacement of the pins therefrom.

The bracket 24 is made to have a suitable length and height so that it may be slipped over the projecting lugs 16 and 17 over the brass 13, the vertically disposed ends 27 and 28 coming up 5 across the respective ends of the lugs and the fingers 29 and 30 extending over the top sides thereof. Preferably, the fingers 29 and 30 are initially turned downwardly slightly so as to require spreading from the bar of the bracket in 10 order to insure a compressive grip on the bracket between the fingers and the under bar.

These gates 23 are assembled on the brass 13 before the brass is inserted into the box 10 over the axle 12. When the brass 13 is in position 15 as indicated in Fig. 1, the bracket 24 in either case can not move toward the axle 12 by reason of the upwardly inclined face of the brass 13 preventing such movement. Neither can the bracket 24 shift outwardly for the reason that 20 it will strike, principally by its under side, the shoulder 14 or 15 as the case may be. Of course longitudinal movement along the brass is prevented by reason of the upturned bracket ends 27 and 28. Therefore, the gates 23 are positioned to hang normally in fixed relationship 25 with the axle and the side wall of the journal box 10. This position is such that the gate 23 on either side of the axle 12, Fig. 1, hangs downwardly vertically and spaced from the axle. This 30 means that the down flowing excess oil is not interfered with, but in fact may be aided by providing a surface down which the oil may flow. Also, each of the plates 23 hangs at a distance inwardly from the projecting wall portions 18 35 and 19. This spacing between the plates and these projecting portions permits the waste packing 11, to be worked down under the axle in the usual manner, by the customary tool or bar without in any way interfering with that action or requiring the handling of either gate 23. The 40 gate 23 on each side is further protected at its wall end by reason of the fact that it hangs behind the annular flange 31 on the outer end of the axle.

Now assuming that the car which is carried by the box 10, is bumped from the right hand side, Fig. 1, the brass 13 will be lifted to leave the axle 12 in a position indicated by the dash lines. Since the gates 23 are hinged to the brass which in this case is the moving part, these gates 45 by reason of their inertia will swing as indicated by the dash lines. Thus, it is to be seen that when the axle 12 pushes down on the waste 11 to form a depression therein to substantially define the dash line position, the displaced waste 50 moving up on the left hand side of the journal at that instant can not enter the opening between the brass 13 and the journal 12 since the gate 23 on that side has swung to the right over toward, if not against, the axle 12 closing off admittance 55 to that opening. Waste coming up therebehind will tend to hold the gate over that opening so as to further prevent the waste from entering 60 therein. The gate 23 on the right hand side of the axle will, of course, not exert any particular effect in this operation. However, since the car is designed to move in either line of travel, a gate 65 must be provided on either side of the axle to take care of the movement of waste when the car is struck from the other side.

It is thus to be seen that when the weight of the car carries the brass 13 back into normal bearing position on the axle 12, the brass will seat on the axle without grabbing any waste 70 therebetween. This action is accomplished with-

out applying any of the heretofore devices directly on the waste in an attempt to hold it down, such devices being ineffective for the reason that they become distorted or broken by the side travel of the axle within the box and further 5 prevent repacking of the box without their removal.

While I have herein shown and described my invention in the best form as now known to me, it is obvious that structural variations may be 10 employed without departing from the spirit of the invention, and I therefore do not desire to be limited to that precise form beyond the limitations as may be imposed by the following claims.

I claim:

1. For preventing waste in a journal box from entering between a lifted brass and a journal, a member swung freely from said brass in the box above the waste between the wall of the box and the side of the journal, said member being hung 20 to allow its lower edge to swing relatively toward said journal under inertia when the journal is suddenly shifted toward the box wall, said member being formed and swung to hang normally clear of said journal.

2. In a journal box, in combination with a journal having waste packing thereunder, and a brass normally bearing on the journal; a plate member carried in hinged relation from the brass to hang freely and swing under inertia effects between the journal and the box wall and normally out of contact with both.

3. In a journal box, in combination with a journal having waste packing thereunder, and a brass normally bearing on the journal; a rigid member carried in freely hinged relation from the brass to hang downwardly between the journal and the box wall, the member having a substantial mass to subject it to swing under inertia effects and having its lower edge spaced normally above and out of contact with said packing to permit free swinging of the member.

4. In a journal box having brass locating shoulders, in combination with a journal having waste packing thereunder, and a brass normally bearing on the upper side of the journal and abutting said shoulders; of a bracket formed to engage said brass and be held thereon against displacement by said shoulders, and a member hingedly carried by said bracket to hang downwardly freely therefrom and proportioned to extend along the major length of said journal but in spaced relation therefrom and to have its lower edge normally above and out of contact with said waste when the brass is normally seated on the journal.

5. In a journal box having brass locating shoulders, in combination with a journal having waste packing thereunder, and a brass normally bearing on the upper side of the journal and abutting said shoulders; of a bracket formed to engage said brass and be held thereon against displacement by said shoulders, and a member hingedly carried by said bracket to hang downwardly freely therefrom and proportioned to extend along the major length of said journal but normally in spaced relation therefrom and to have its lower edge above and out of contact with said waste when the brass is normally seated on the journal, and friction members engaging said bracket initially with said brass.

6. For preventing waste grabs in a journal box having a journal and a journal brass therein, a brass engaging bracket, and a member freely swung downwardly from the bracket and com- 75

prising a metal plate approaching the length of the brass and having bracket engaging portions at its upper ends.

7. For preventing waste grabs in a journal box having a journal and a journal brass therein, a brass engaging bracket, and a member freely swung downwardly from the bracket, said brass having side projecting lugs, and members on said bracket for engaging over said lugs.

8. For preventing waste grabs in a journal box having a journal and a journal brass therein, a brass engaging bracket and a member freely swung downwardly from the bracket, said brass having side projecting lugs, and said bracket being formed substantially U-shaped to fit under and around said lugs to provide against longitudinal travel along the brass and having inturned fingers fitting over onto the upper side of the lugs.

9. For preventing waste grabs in a journal box having a journal and a journal brass therein, a brass engaging bracket and a member freely swung downwardly from the bracket, said brass having side projecting lugs, and said bracket

being formed substantially U-shaped to fit under and around said lugs to provide against longitudinal travel along the brass and having inturned fingers fitting over onto the upper side of the lugs, said member having hinge pins engaging into sockets in the upturned legs of the bracket, and said pins and sockets being fitted to permit the upper edge of said member to bear against the bracket when the member may be upwardly lifted.

10. For preventing waste in a journal box from entering between a lifted brass and a journal, a member swung to hang freely in the box normally clear of the waste and between the wall of the box and one side of the journal, a like member swung in like manner on the other side of the journal whereby one of said members may swing toward the journal when the journal is suddenly shifted thereaway, and the other of said members may swing toward the journal box 20 wall on the other side under the influence of inertia.

WILLIAM T. BISSELL.
